Res. J. W. M. Deneck

B. L. SOUTHACK, OF NEW YORK, N. Y.

Letters Patent No. 87,216, dated February 23, 1869.

IMPROVED SOFA-BED.

The Schedule referred to in these Letters Patent and making part of the same.

To all whom it may concern:

Be it known that I, B. L. SOUTHACK, of the city, county, and State of New York, have invented a new and improved Sofa-Bed; and I do hereby declare that the following is a full, clear, and exact description thereof, which will enable those skilled in the art to make and use the same, reference being had to the accompanying drawings, forming part of this specification, in which—

Figure 1 represents a vertical transverse section of my improved sofa-bed, showing it folded together.

Figure 2 is a similar view, showing it extended.

Figure 3 is a vertical longitudinal section of the same, taken on the plane of the line $x x$, fig. 1.

Similar letters of reference indicate corresponding parts.

The object of this invention is to construct a sofa-bed, in which the back of the sofa is used to form part of the bed-bottom, so that, in order to convert the sofa into a bedstead, the whole article has not to be moved from the wall near which it stands.

This is a great inconvenience in the sofa-beds now in use, and to overcome it is the chief object of my invention.

My invention consists, principally, in so connecting the back with the seat-portion of the sofa, and in so constructing the said back, that when the seat is pulled out of the sofa-frame, the back will be swung or brought down into the former place of the seat, to become part of the bed-bottom, this whole operation being carried on without disturbing the sofa-frame.

A, in the drawing, represents the frame of my improved sofa-bed.

It consists of the side-pieces $a a$, connected by the front and back planks $b c$, and forming the head and foot-rests, or arm-supports $d d$.

It is made of wood or other suitable material, of suitable design and form.

B is the seat of the sofa.

The same consists of slats or boards $e e$, which are secured at the ends to boards or planks $f f$, that fit against the arm supports $d d$, as shown.

To the front edges of the planks f are secured upright posts $g g$, which extend to the floor in front of the frame A, and which may be connected by means of

a board, h , in front of b , as is clearly shown in figs. 1 and 2.

The seat can be locked to the frame by means of a hook, i , shown in fig. 1, or by a bolt, or other means.

The posts g should be provided with casters, so that the seat-frame can be easily pulled out from the main frame, as in fig. 2.

The back, C, of the sofa is made of slats, which are hinged together, or connected by flexible bands $j j$, so that the back will thus become flexible. It is hinged to the seat, so as to be drawn out with the same.

When the instrument is contracted into a sofa, as in fig. 1, the back, C, will, with its ends, fit into grooves that are formed in posts $h h$, projecting in rear from the frame A.

The upper ends of said posts may be connected by means of a horizontal or other bar, l , as shown.

The lower ends of the grooves in h are rounded, as shown, so that when the seat is drawn out, as in fig. 2, the back may readily follow, to occupy the former place of the seat.

Both the back and the seat may be upholstered in any suitable manner.

It will be noticed that the sofa can be readily converted into a bedstead without disturbing the main frame A.

The seat can be so arranged that it may be swung open when on the sofa, to allow the bedding under it to be taken out or put into the lounge.

I claim as new, and desire to secure by Letters Patent—

1. A sofa-bed, so arranged that the back will, when the seat is drawn out, follow the same, and form part of the bed-bottom, as set forth.

2. The slat-back C of a sofa-bed, arranged and operating substantially as herein shown and described.

3. The combination, in a sofa-bed, of the stationary frame A, sliding seat-frame B, and rolling back C, all made and operating substantially as herein shown and described.

B. L. SOUTHACK.
